CLAIM

The ornamental design for a vehicle tire, as shown and described.

DESCRIPTION

FIG. 1 is a perspective view of a tire showing my new design, it being understood that the tread pattern is repeated throughout the circumference of the tire, as shown schematically by the solid lines, the opposite side being the same as the side shown;

FIG. 2 is an enlarged fragmentary side elevational view thereof; and

FIG. 3 is an enlarged fragmentary plan view thereof.
